(57) **CLAIM**

The ornamental design for a toy race track bottleneck segment, as shown and described.

DESCRIPTION

FIG. 1 is a top, front perspective view of the toy race track bottleneck segment, showing my new design;

FIG. 2 is a front view of the toy race track bottleneck segment;

FIG. 3 is a rear view of the toy race track bottleneck segment;

FIG. 4 is a top view of the toy race track bottleneck segment;

FIG. 5 is a bottom view of the toy race track bottleneck segment;

FIG. 6 is a right side view of the toy race track bottleneck segment; and,

FIG. 7 is a left side view of the toy race track bottleneck segment.

The broken lines in the drawings illustrate environment and portions of the toy race track bottleneck segment that form no part of the claimed design.
